(57) **CLAIM**

The ornamental design for a hoodtray, as shown and described.

DESCRIPTION

FIG. 1 is a top plan view of the hoodtray showing my novel design;

FIG. 2 is a bottom plan view thereof;

FIG. 3 is a left end view thereof;

FIG. 4 is a right end view thereof;

FIG. 5 is a front elevational view thereof;

FIG. 6 is a rear elevational view thereof;

FIG. 7 is a perspective view of the hoodtray of the present invention; and,

FIG. 8 is a perspective view of the hoodtray of the present invention as shown mounted on the hood of a police vehicle. The broken lines shown in FIG. 8 are for illustrative purposes only and form no part of the overall claimed design.
